UNITED STATES PATENT OFFICE.

ERWIN A. LOCKWOOD, OF ROYAL OAK, MICHIGAN, ASSIGNOR TO AMERICAN ELECTRICAL HEATER COMPANY, OF DETROIT, MICHIGAN, A CORPORATION OF MICHIGAN.

ELECTRIC SOLDERING IRON.

Application filed November 22, 1926. Serial No. 150,018.

The invention relates to electrically heated instruments and more particularly to electric soldering irons of the type in which a central metallic core member is heated by an electrical resistor surrounding the same in close proximity thereto.

With instruments of this type as heretofore constructed it has been the usual practice to form the electrical resistor by winding a conductor circumferentially of the core member and spaced therefrom only by a thin layer of insulation, such as mica. When such a construction is subjected to alternate heating and cooling, it has been found that 10 the metallic conductor gradually contracts in length and this contraction increases the tension on the windings so that they are drawn more tightly around the rigid core member. Since this core member is unyielding, the tension sometimes increases to such 20 an extent that a failure occurs, thus destroying the resistor and requiring a replacement unit.

The primary object of this invention is to 25 provide an improved resistor construction so arranged as to permit contraction of the windings under various temperature conditions without placing any material additional tension on the conductor, thus avoiding all danger of breakage from this cause. This object has been attained by providing the novel construction hereinafter more fully described, which consists essentially in arranging the 30 windings to extend longitudinally of the core and to be spaced circumferentially thereof. The conductor is preferably wound upon a tubular insulating member, which, while normally holding the windings in fixed relation, is nevertheless sufficiently yieldable to 35 permit lengthwise contraction of the conductors without subjecting them to any increased tension.

In the drawings:

Figure 1 is a longitudinal section through 45 the soldering iron;

Figure 2 is a perspective view showing the method of assembling the resistor on the core;

Figure 3 is a view of the resistor as wound 50 prior to being formed into a tube;

Figure 4 illustrates the resistor after being formed into a tube.

In the preferred embodiment of my invention as illustrated in the drawings, A represents the hollow cylindrical metallic core

preferably formed of a material resistant to high temperatures. B is the metallic tip inserted within said core and removably secured thereto by suitable means, indicated as the set screw C. The middle portion of 60 the core member A is of smaller diameter, as indicated at D, forming a spool for receiving the tubular resistor E. F is a threaded core projection extending from the rear end of the core and threaded to receive a hollow handle 65 shank G. H is the outer shell sleeved on the forward portion of the core and retained in position by the lock nut H'.

The resistor D is preferably formed as illustrated in Figure 3 by winding a resistance 70 element on a flat rectangular sheet of insulating material, such as mica. This flat sheet I is provided with notches J on its opposite edges which receive the windings K. The resistance element is preferably in the form of a 75 flat ribbon L and this is wound around the flat sheet I forming a continuous resistance unit. After the resistance element has been wound on the flat sheet, the latter is bent into tubular form with the windings extending longitudinally thereof. The opposite edges M and M' of the sheet are brought together, forming a split tube which is placed around the spool portion of the core A. For 80 insulating the resistor from the core it is preferable to insert a layer of mica N between the core and the tubular resistor and a similar 85 layer of mica O is wrapped around the outside of the resistor. Surrounding the insulation O a metallic sheet P is placed and the 90 whole structure is retained in assembled position by a binding of wire, as indicated at Q, the convolutions extending circumferentially.

With the construction described it will be 95 apparent that any contraction of the resistor windings due to alternate heating and cooling of the instrument will tend to shorten the windings in a direction longitudinally of the core and this is permitted due to the yieldable nature of the mica tube on which the 100 resistor is wound. This contraction, however, has no material effect on the tension of the resistance ribbon and the spacing of the windings circumferentially of the core remains the same.

In order to bring the terminals from the resistor out through the handle shank, it is preferable to have the windings leave the tubular insulating member on which they are wound from diametrically opposite points 105 110

- thereof. For accomplishing this purpose the windings on the mica sheet I are of slightly shorter lengths for one-half of the circumference of the tube than for the other half, leaving a semi-circular portion R between the ends of the windings and the edge of the tube. The terminal S is transversely bent at S' and arranged circumferentially of the tube in the portion R and again transversely bent at S² to extend outwardly from the tube. The other terminal T is directly extended outward from the tube at the edge M, the arrangement being such that the two terminals leave the tube at diametrically opposite points. The terminals at these points are encased, preferably in an armor U, and are threaded through inclined passageways V in an insulator block V'. The terminal construction at this point is similar to that described in Patent No. 1,425, 20 983.
- From the above description it will be apparent that I have provided a resistor construction which can be assembled on a central core in a manner to possess all of the advantages of the usual circumferentially wound resistor, but which has in addition the further advantage of being free from strains set up by the contraction of the metal in the conductors after repeated use.
- 30 What I claim as my invention is:
1. A resistor unit for electrically heated instruments having a cylindrical core, said unit including a tubular resistance element surrounding said core and formed of a mica sheet 35 having a conductor wound around the same with the windings extending longitudinally and spaced circumferentially thereof, and a binding member surrounding said tubular resistance unit and insulated therefrom.
  - 40 2. A resistor unit for electrically heated instruments having a cylindrical core, said resistor unit comprising a thin sheet of insulating material wrapped around said core to surround the same, a conductor wound around 45 said sheet, the windings extending longitudinally of said core and being spaced circumferentially thereof, insulating material on the inner and outer sides of said resistor, a metallic sheet wrapped around said resistor unit, 50 and a binding element surrounding said sheet and wound circumferentially thereof.
  - 55 3. A resistor unit for electrically heated instruments having a cylindrical core, said unit including a thin-walled tube of insulating material, a conductor wound on said tube with windings extending longitudinally and spaced circumferentially, the windings of one end of said tube extending further longitudinally for one-half of the circumference than the other half, one terminal from said windings being extended circumferentially of said tube to a point diametrically opposite the other terminal, and a bushing carried by said core at the terminal end of said windings and provided with inclined passageways for said terminals.
  - 60 4. A resistor unit for electrically heated instruments having a cylindrical metallic core, said unit comprising a tubular insulator surrounding said core, a resistance element 70 wound on said insulator with the windings extending longitudinally and spaced circumferentially thereof, the windings being return bent over the edges of said tube and the return-bent portions on one half the circumference projecting further longitudinally than on the other half, one of the terminals of said windings extending circumferentially of said tubular insulator adjacent the return-bent portions of shorter length, said terminal leaving said tubular insulator at a point diametrically opposite the other terminal.
  - 75 5. A resistor unit comprising a sheet of insulating material formed into a tube, a flat conductor ribbon wound on said sheet to extend longitudinally thereof, the windings being spaced circumferentially of the tube and extending for substantially the entire periphery thereof, the opposite ends of said windings terminating at adjacent points and 80 one of said ends being carried circumferentially of said tube to a point diametrically opposite the other.
  - 85 6. A resistor unit for electrically heated instruments having a core, said unit including an insulator surrounding said core, a conductor wound on the insulator with the windings extending longitudinally thereof, the said windings varying in length adjacent one end of said insulator for the purpose set forth.
  - 90 7. A resistor unit for an electrically heated instrument having a core, said unit including a substantially cylindrical insulator surrounding said core, and a resistor wound on said insulator with the windings extending longitudinally on opposite sides thereof.

In testimony whereof I affix my signature.
ERWIN A. LOCKWOOD.
